UNITED STATES PATENT OFFICE

JACOB HENRY BECKMAN, OF OAKLAND, CALIFORNIA

AMMONIA CONDENSER

Application filed December 17, 1929. Serial No. 414,704.

This invention relates to ammonia condensers of the type disclosed in United States Letters Patent #1,716,681 issued to me on June 11, 1929.

5 It is the principal object of the present invention to generally improve condensers of the type referred to whereby to increase the capacity and efficiency thereof.

One form which the invention may assume 10 is exemplified in the following description and illustrated by way of example in the accompanying drawings, in which:

Fig. 1 is a diagrammatic illustration of 15 my improved type of ammonia condenser with parts in section to more clearly disclose certain novel features of construction.

Fig. 2 is a front elevation of the condenser with parts broken away to more clearly disclose its construction.

20 Fig. 3 is a vertical transverse section taken through the condenser on line III—III of Fig. 2.

Fig. 4 is an end elevation of the condenser with one of the drums in section.

25 Fig. 5 is a vertical section through the tube unit taken on line V—V of Fig. 2.

Fig. 6 is a fragmentary view in section showing the connection between one of the tubes and one of the headers.

30 Referring more particularly to the accompanying drawings, 10 and 11 indicate a pair of horizontally disposed cylindrical drums arranged in parallelism. Headers 12 and 14 are connected at their lower ends to the drums 35 10 and 11 and extend vertically therefrom.

A plurality of horizontally disposed tubes 15 are connected at their opposite ends to the headers 12 and 14 and are arranged at equally spaced distances apart along the headers as 40 illustrated most clearly in Figs. 2 and 5. The headers and the tubes comprise the tube unit of the condenser.

Arranged beneath the tube unit is a water reservoir 16. This reservoir is connected by 45 a pipe 17 to a circulating pump 18 the exhaust port of which is connected by a conduit 19 to the inlet 20 of a distributor 23 disposed above the tube unit. A supply line 21 is connected with the pipe 19 so that additional water may be supplied to the circulat-

ing system when desired. The sides of the tube unit are enclosed by panels 22 which extend between the vertical headers 12 and 14.

Water from the reservoir 16 is drawn therefrom by the pump 18 and discharged from the pipe 19 through the distributor 23 which distributes the water over the entire length of the tubes 15. The water so distributed is trapped and caused to pass over the surface of each tube 15 by means of obliquely arranged baffles 24 extending longitudinally as illustrated in Fig. 5. Thus, the water from the pump is caused to travel over the surfaces of the tubes to effect an exchange of heat, which water is trapped by the reservoir 16 and recirculated.

To increase the efficiency of the condenser I cause an air flow to travel upwardly around the tubes 15 in a counter direction to the water. This air flow is induced by a blower or air pump connected by a conduit 25a with the bottom of the casing which houses the tube unit and forces air into the tube unit casing, which air passes upwardly through the tube unit and is discharged from a discharge connection 25 at the top of the housing. Baffles 26 extend longitudinally within the housing intermediate the baffles 24. The baffles 26 extend inwardly from the sides of the casing 50 which houses the tube unit.

The provision of these baffles causes the upwardly flowing air to impinge against the water passing over the tubes 15 and thus effects an exchange of heat, serving to maintain the water cool so that greater efficiency in condensing the ammonia in the tubes will be obtained.

The ammonia gas to be condensed is discharged from the ammonia plant 30 through 60 a pipe 31 which is connected with the drum 10. This drum is interiorly fitted with a baffle 32 and the overflow connection thereto is so disposed that a quantity of liquid ammonia is always present in the drum. The 65 gas discharging into the drum 10 from the pipe 31 must pass through this liquid ammonia in order to pass through the drum due to the provision of the baffle 32. The 70 level of the liquid in the drum 10 may be 75 80 85 90 95 100

maintained at a predetermined level by means of an overflow pipe 33 fitted with a control valve 34. By opening the valve 34 the overflow in the drum 10 may be diverted to the drum 11. Each drum 10 and 11 is fitted with a drainage valve so that oil in the ammonia may be drawn off.

After the ammonia gas, which is superheated, passes into the drum 10 it is forced to pass into the liquid ammonia therein. This converts the superheated gas into a saturated vapor which passes upwardly into the header 12 and into the tubes 15. By passing the gas through the liquid in the drum 10 I am enabled to condense the gas to a liquid approximately eight times faster than if the superheated gas from the ammonia plant was directed directly to the tubes 15.

Another advantage of passing the gas through the liquid ammonia is that the oil which is usually carried by the gas in a plant of this type is separated from the gas and settles in the drum 10. In other words the gas is washed before it enters the condenser. The oil that gathers in the drum 10 in this manner and any oil that may overflow into the drum 11 through the pipe 33 may be detected by means of liquid level gauges 41 attached to the drums 10 and 11. The drainage valves 40 on the drums may be opened to draw the oil from the drums at necessary intervals.

At the point where the pipes or tubes 15 are connected with the header 12, each tube is fitted with a baffle 15a which prevents any liquid accumulating in the tubes 15 from discharging back into the header 12. As the gas rises in the header 12 and passes through the tubes 15, the passing of the water over the tubes and the cooling influence of the upward current of air causes an exchange of heat which condenses the saturated vapor into liquid which liquid discharges into the header 14 and thus into the drum 11. From this drum it may be drawn off by a pipe 35 and returned to the ammonia plant. I desire to point out that the gas in passing through the tubes 15 is condensed and gives up its latent heat and the condensate is cooled.

By my construction as hitherto described I am enabled to effect a great saving in water and it is unnecessary to provide a cooling tower or other apparatus for cooling the water after it has passed over the condenser tubes. This, of course, is a considerable saving over prior devices.

I have found in actual practice that by using a given quantity of water I can continually recirculate this water with a very small loss. Likewise, by the provision of the upwardly passing air the water is maintained at a comparatively low temperature and the ammonia gas is efficiently condensed.

While I have shown the preferred form of

my invention, it is to be understood that various changes may be made in its construction by those skilled in the art without departing from the spirit of the invention as defined in the appended claims.

Having thus described my invention, what I claim and desire to secure by Letters Patent is:

1. In an ammonia condenser, a plurality of heat exchanging tubes, means causing a flow of cooling liquid over said tubes, baffles directing the liquid toward the tubes, means for causing a current of air to pass over said tubes in a counter direction to the cooling liquid, and baffling means for causing the current of air to impinge against the tubes and the first named baffles. 70 75

2. In a device of the character described, a condensing means, means for conveying a cooling liquid over said condensing means, baffle plates directing the liquid onto the condensing means, means for allowing a current of air to pass said condensing means, and other baffling means whereby the current of air will be directed against said condensing means and cooling mechanism. 85 90

3. In a device of the character described, the combination of a pair of headers, condensing means forming communication between the headers, means for admitting a gas to said condensing means, means whereby the gas will be desuperheated before entering said condensing means, means for conveying a cooling liquid over said condensing means, means whereby air will be directed against said condensing means and said cooling liquid and a set of baffle plates arranged in staggered relation, whereby alternate plates will direct the flow of the liquid and the remaining plates will direct the flow of air. 95 100 105

4. In a device of the character described, the combination of a pair of headers, condensing means forming communication between the headers, means for admitting a gas to said condensing means, means connected with one of said headers whereby a gas passing through the header will become desuperheated means for conveying a cooling liquid over said condensing means, a casing arranged around the condensing means and containing baffles to direct the flow of liquid to the condensing means, means for forcing air upwardly through said casing, and baffles carried by the walls of the casing and arranged alternately with said first baffles to direct the air against the first baffles and against the condensing means. 110 115 120

JACOB HENRY BECKMAN.
